US0D1051145S

(12) **United States Design Patent** (10) **Patent No.:** **US D1,051,145 S**
McIver et al. (45) **Date of Patent:** **** Nov. 12, 2024**

(54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **Jordan McIver**, Blaine, MN (US); **Michael Coleman**, Shoreview, MN (US); **John Rondoni**, Plymouth, MN (US); **Isabel Ancona**, Boston, MA (US)

(73) Assignee: **INSPIRE MEDICAL SYSTEMS, INC.**, Golden Valley, MN (US)

(**) Term: **15 Years**

(21) Appl. No.: **29/853,408**

(22) Filed: **Sep. 15, 2022**

Related U.S. Application Data

(63) Continuation of application No. 29/772,824, filed on Mar. 4, 2021, now Pat. No. Des. 966,307.

(57) **CLAIM**

The ornamental design for a display screen or portion thereof with a graphical user interface, as shown and described.

DESCRIPTION

FIG. 1 is a front view of a display screen or portion thereof with a graphical user interface showing our new design; and, FIG. 2 is a front view of a second embodiment thereof. In the FIGURES, the outermost broken lines show a display screen or portion thereof and form no part of the claimed design. The remaining broken lines show elements of the graphical user interface that form no part of the claimed design.

1 Claim, 2 Drawing Sheets
